UNITED STATES PATENT OFFICE.

JAMES E. SALSMAN, OF CRESCENTVILLE, OHIO, ASSIGNOR OF ONE-TWELFTH TO W. S. ROWE AND FIVE-TWELFTHS TO HAROLD W. NICHOLS, BOTH OF CINCINNATI, OHIO, AND ONE-FOURTH TO HARRY B. JONES, OF ARLINGTON, OHIO.

TUB-BEATER.

1,338,869.

Specification of Letters Patent.

Patented May 4, 1920.

Application filed April 29, 1918. Serial No. 231,387.

To all whom it may concern:

Be it known that I, JAMES E. SALSMAN, a citizen of the United States, and a resident of Crescentville, in the county of Hamilton and State of Ohio, have invented certain new and useful Improvements in Tub-Beaters, of which the following is a full, clear, and exact description, reference being had to the accompanying drawings, forming part of this specification.

My invention relates to improvements in the construction of the ordinary tub beater which in paper mills is employed for the reduction of paper stock to pulp of the desired condition for use in the subsequent paper making processes. The ordinary method consists in grinding and beating up the paper stock with water in an oblong tub and continuing the process until the entire mass has been reduced to the proper consistency.

Efforts in the past have been made to provide devices with which, without interrupting the grinding of the stock, the finished material may be drawn off while fresh paper stock is added to the beater so that without stopping the machine the process may be continuous and the finished stock may be removed continuously, but my invention has the advantage of working on much more varied grades of stock and without becoming continually clogged when on certain rough or cheap grades of stock.

It is the object of my invention to provide a novel separator which will be free from the objections heretofore encountered, to be applied to the ordinary tub beater without change or modification thereof, by which the finished stock may be continuously withdrawn from the beater without stopping the beater, and with which devices in the preferable construction, the movement of the stock in the beater may be accelerated and the finished stock prepared in less time than with the ordinary apparatus, and in which less power and not so close application of grinding surfaces are required.

In the drawings,

50 Figure 1 is a top plan view of the beater, with my improvements applied thereto.

Fig. 2 is an end elevation.

Fig. 3 is a perspective view of the apparatus for extracting the finished stock.

Fig. 4 is a plan view of the same, with the cylindrical casing removed.

Fig. 5 is an end elevation, with the end wall removed.

The ordinary elongated tub 1 is provided with the usual mid-feather 2 to permit circulation of the paper stock as it passes under the beating roll 3, which is mounted on the shaft 4 suitably journaled across the middle of the machine and driven in any ordinary way, usually by belt 5 and pulley 6. The beating roll 3 is provided with the usual knives 19 which coöperate with the usual bed plate in the bottom of the machine for cutting and tearing up the paper stock, and the material is carried over the usual back-fall 7 and circulates slowly around the mid-feather in the direction of the arrow and back again to the beating roll. The stock is usually introduced at one end of the tub, where water for digesting the material is also introduced. There is also indicated at 8 an additional water pipe for supplying streams of water to the material just before it passes under the beating roll.

All the foregoing are the ordinary and usual constructions of tub beaters which have long been in use.

In order to withdraw the finished stock continuously, I provide a cylindrical separator 9, which is mounted on the shaft 10, one end of which is journaled on the mid-feather, and the other journal is located on the side of the tub. This shaft with the cylindrical separator is driven in any ordinary way from the power plant, as indicated by the belt 11 and pulley 12. The cylindrical separator is in its internal construction made up of circular heads or ends 13, 14, with longitudinal partitions 15, 15, dividing the cylindrical space into a number of compartments. As a preferable construction, I employ six of these radial partitions, making six compartments in the complete cylinder. The floor or bottom of these compartments slopes from one end of the cylinder near the periphery at 16 downwardly toward the axis of the cylinder at 17 at the other end. The chambers of the cylinder are covered and inclosed by a smooth cylindrical casing 20 preferably of sheet metal or any other suitable material, while the casing is to be smooth on the outside. The casing is provided with a series of per-

forations or openings 21, with the longitudinal rows arranged in staggered relation to each other, and where six compartments are provided there are six sets of these perforations with intermediate unperforated portions. The cylindrical casing is so applied that the perforated portions will lie for the most part on the upper side and some distance above the respective partitions 15 so that the unperforated portion of the cylinder will form with the partitions 15 pockets to receive and hold the material which enters through the openings as the separator is rotated in the stock, as will be hereinafter described. Each of the compartments is provided with an opening at its lower or delivery end and the side wall of the tub forms a closure for these openings when below the top edge of the tub, while the edge at the upper portion of the cylinder is extended upward to form a wall 13^a to close the openings when they are above the edge of the tub. The wall 13^a is provided with a discharge opening 22 which is closed by a sliding gate 23 operated in any convenient way, and as illustrated in the drawings by the bar 24, which is pivoted on the framework and provided with a slotted arm in engagement with the gate, so that by raising and lowering the arm, the gate will be opened and shut, the gate being guided in the framework 23. Outside of the tub to receive the material discharged from the separator through the gate any convenient arrangement may be provided for carrying off the finished stock for subsequent treatment in the paper making processes. I have illustrated a trough 25 for carrying off the material.

Secured across the rear side of the cylinder running longitudinally therewith and bearing against the cylinder, is a scraper 26 of any convenient form. I have illustrated a bar or doctor, but stiff wire brushes may be employed, or other means for removing from the cylinder as it is rotated any strings, rope or other material that may have a tendency to clog the perforations. As illustrated in the drawings, the scraper bar is mounted on a pair of rock arms 27, pivoted at the upper edge of the tub and the mid-feather, and coiled springs 28 bearing on these arms outside the fulcrum point tend to hold the scraper with spring pressure against the cylinder, to permit it to give against any too great accumulation.

With the perforated cylinder mounted as described, it is slowly rotated in the preferred method in the direction of the current of the material caused by the action of the roll beater, at a speed slightly in excess of the flow that would be created by the beater alone, so that the rotation of the roll has the effect of accelerating the flow. The surface of the cylinder being smooth, the

finished stock by the movement of the cylinder is pushed through the perforations into the compartments of the cylinder, is carried up to the top of the cylinder by the pockets formed between the partitions and the unperforated portion of the cylinder and flows down to the gate whence it is delivered into the trough 25. It will be understood, however, that the cylinder may be rotated in the opposite direction. 75

Inasmuch as the cylinder is smooth and circular in cross section, any strings or material that would clog the perforations is removed and drops back into the current to be carried again to the beater roll. The smoothness of the surface assists in preventing the carrying over the cylinder or accumulation on the cylinder of surplus material and tends to regulate the amount and evenness of flow into the interior. 80

Having thus described my invention, what I claim as new and desire to secure by Letters Patent, is:—

1. In a tub beater, a separator for the finished stock comprising a hollow cylindrical roll mounted transverse the tub and adapted to be rotated in the paper stock, said cylinder having a smooth exterior, with perforations for the cylinder of a size to allow the finished stock to enter the cylinder 90 and reject the unfinished stock, and means for discharging same therefrom. 95

2. In a tub beater, a separator for the finished stock comprising a hollow cylindrical roll mounted transverse the tub, partially submerged in the contents thereof, and adapted to be rotated in the paper stock, said cylinder having a smooth exterior, with perforations for the cylinder of a size to allow the finished stock to enter the cylinder during the rotation thereof and reject the unfinished stock, and means for discharging same therefrom. 100

3. In a tub beater, a separator for the finished stock comprising a hollow cylindrical roll mounted transverse the tub and adapted to be rotated in the paper stock, said cylinder having a smooth exterior, with the interior divided into a series of compartments, with perforations for the cylinder of a size 110 to allow the finished stock to enter the cylinder during the rotation thereof and reject the unfinished stock, and means for discharging same therefrom. 115

4. In a tub beater, a separator for the finished stock comprising a hollow cylindrical roll mounted transverse the tub and adapted to be rotated in the paper stock, said cylinder having a smooth exterior, with the interior divided into a series of compartments by longitudinal partitions having floors inclined toward one end of the cylinder, with perforations for the cylinder of a size to allow the finished stock to enter the cylinder during the rotation thereof and 120

125

130

reject the unfinished stock, and means for discharging same therefrom.

5. In a tub beater, a separator for the finished stock comprising a hollow cylindrical roll mounted transverse the tub and adapted to be rotated in the paper stock, said cylinder having a smooth exterior, with perforations for the cylinder to allow the finished stock to enter the cylinder, means 10 for discharging same therefrom, and with means for preventing the clogging of the perforations during the operation.
6. In a tub beater, the combination with the beater, of a separator for the finished stock comprising a hollow cylindrical roll mounted transverse the tub, partially submerged in the contents thereof, and adapted to be rotated in the paper stock, said cylinder having a smooth exterior, with the interior 15 divided into a series of compartments by longitudinal partitions and having floors inclined toward one end of the cylinder, with perforations for the cylinder to allow the finished stock to enter the compartments 20 alternating with blank portions to serve as pockets with the partitions to hold the stock and carry it to the upper portion of the cylinder, said perforations being adapted to reject the unfinished stock, and means for 25 discharging the same therefrom.
7. In a tub beater, the combination with the beater, of a separator for the finished stock comprising a hollow cylindrical roll mounted transverse the tub, partially submerged in the contents thereof, and adapted to be rotated in the paper stock, said cylinder 30 having a smooth exterior, with the interior divided into a series of compartments by longitudinal partitions and having floors inclined toward one end of the cylinder, with perforations for the cylinder to allow the finished stock to enter the compartments 35 alternating with blank portions to serve as pockets with the partitions to hold the stock and carry it to the upper portion of the cylinder, means for discharging same therefrom, and with means for preventing the clogging of the perforations during the operation.
8. In a tub beater, the combination with the beater, of a separator for the finished stock comprising a hollow cylindrical roll mounted transverse the tub, partially submerged in the contents thereof, with one head for the cylinder rotating therewith and 40 the other head stationary, with the tub provided with a gate therein, and the cylinder adapted to be rotated in the paper stock, said cylinder having a smooth exterior with the interior divided into a series of compartments by longitudinal partitions and having floors inclined toward one end of the cylinder, with perforations for the cylinder to allow the finished stock to enter the compartments 45 alternating with blank portions to serve as pockets with the partitions to hold the stock and carry it to the upper portion of the cylinder, and with means for preventing the clogging of the perforations during the operation.

JAMES E. SALSMAN.
